188,964

SPACE VEHICLE OR SIMILAR ARTICLE

William C. House, Claremont, and Gerald F. Binnings,
Arcadia, Calif., assignors to Aerojet-General Corporation,
Azusa, Calif., a corporation of Ohio

Filed Apr. 13, 1959, Ser. No. 55,465

Term of patent 14 years

(Cl. D71—1)

Des. 188,964

PAGE 2

Fig. 1 is a side elevational view of the space vehicle showing our new design;

Fig. 2 is a front elevational view of the space vehicle;

Fig. 3 is a rear elevational view thereof;

Fig. 4 is a side elevational view of the space vehicle showing the side opposite that shown in Fig. 1; and

Fig. 5 is a bottom elevational view thereof.

We claim:

The ornamental design for a space vehicle or similar article, as shown.
